UNITED STATES PATENT OFFICE

2,631,010

PORTABLE HOIST

Hayes W. Beatty, Ivanhoe, N. C.

Application June 23, 1950, Serial No. 169,983

1 Claim. (Cl. 254—139.1)

1

This invention relates to a portable hoist or lift designed for attachment to a tractor.

An object of this invention is to provide a portable hoist or a crane which can be attached to a tractor and connected with the power take-off so that logs or other articles may be raised and moved.

Another object of this invention is to provide a portable hoist or crane which can be used for lifting and carrying small logs or the like in swampy territory so that the logs may be moved to higher ground.

A further object of this invention is to provide a device of this kind which is of simple construction and which includes a hydraulic brake for the hoisting drum which is connected to the hydraulic pressure system of the tractor.

With the above and other objects in view, my invention consists in the arrangement, combination and details of construction disclosed in the drawings and specification, and then more particularly pointed out in the appended claim.

In the drawings:

Figure 1 is a detailed side elevation of a portable hoist or crane constructed according to an embodiment of this invention.

Figure 2 is a plan view of the device.

Figure 3 is a fragmentary sectional view taken on the line 3—3 of Figure 1.

Figure 4 is a sectional view taken on the line 4—4 of Figure 1.

Figure 5 is a fragmentary sectional view taken on the line 5—5 of Figure 2.

Referring to the drawing the numeral 10 designates generally an elongated tubular boom or frame member which is secured to an inverted U-shaped frame or bolster 11. The frame or bolster 11 has secured to the lower portions of the legs 12 thereof spindles 13, and wheels 14 are rotatably carried by spindles 13. The bight or upper bar 15 of the frame member 11 has secured thereto an upstanding plate 16 through which the boom 10 engages and the boom 10 is firmly secured as by welding or the like to the plate 16.

The rear end of the boom 10 has secured thereto a substantially U-shaped hitch supporting member 17, and a coupling member 18 is pivotally connected by means of a pivot 19 to a right angularly disposed pivot 20 which extends through a pair of ears 21 fixed to the U-shaped member 17. The boom member 10 is braced by means of a truss rod 22 which is fixed to the upper side of the boom 10 at the opposite ends thereof and is braced relative to the boom 10 and the frame

2

11 by means of upwardly convergent bracing bars 23.

5 A winding drum 24 is rotatably mounted on a horizontally disposed and transversely extending shaft 25 which is journalled in bearings 26 carried by supporting members 27. The supporting members 27 are of substantially U-shape and are secured to a rectangular frame 28 which is disposed rearwardly of the inverted frame member 11 and is fixed relative to the boom 10.

10 As shown in Figure 3 the boom 10 extends through and is fixed in the transversely extending end members 29 which, with the outer side members 30, form the frame 28. The bearing supporting members 27 are also braced by means of downwardly and rearwardly inclined bracing bars 31 which are secured to the forward portions of the supporting members 27 and are secured to the outer portions of the frame member 11.

15 20 The shaft 25 has fixed thereon a bevel gear 32 disposed in a housing 33, and a gear 34 is fixed on a shaft 35 journalled through the housing 33 and rotatably engaging through a tubular housing 36 which extends rearwardly of the gear housing 33. The shaft 35 has connected with the rear end thereof a universal joint 37 which has an extension shaft 38 connected therewith, and the extension shaft 38 is adapted to be connected to the power take-off of a tractor.

25 30 A clutch member 39 of conventional construction is connected with the shaft 25, and the winding drum 24 and an upwardly projecting clutch lever 39a extends from the clutch 39 in a position convenient to a person standing on a platform P which is fixed in rearwardly projecting position with respect to bearing supporting members 37 and the boom 10.

35 40 The frame member 11 is braced relative to the boom 10 by means of a pair of rearwardly divergent bracing bars 40 secured at their forward ends to the boom 10 at the forward end of the latter, and the bracing bars 40 are fixed at their rear ends to the outer portions of the inverted U-frame 11. Rearwardly convergent bracing bars 41 are fixed at their forward ends to the frame member 11 and to the outer sides of the winch supporting frame 28. A pair of bracing bars 42 are also fixed between the rearwardly divergent bracing bars 40 and the boom 10.

45 50 A hydraulic brake structure 43 of conventional construction is correlated with the winding drum 24 at the end thereof opposite from the clutch 37 and is adapted to be connected by pipes 44 to a pressure supply source which is available on the tractor. A suitable valve (not shown) is

connected to the pressure lines 44 so that the hydraulic brake may be operated at will.

In the use and operation of this portable hoist which is commonly termed a snaking horse, the rear end of the hoist is connected by the coupling member 18 to the rear end of the tractor. The cable 45 which is wound on the drum 24 is extended over a grooved pulley 46 carried by a clevis 47 pivotally secured to the forward end of the boom 10. The cable 45 has secured to the forward end thereof a log clamping tong 48.

Shaft 33 is operated from the power take-off and with clutch lever 39a swung to a clutching position, drum 24 will be rotated to wind cable 45 about the drum and raise the clamping or gripping member 48. The log in raised position may then be moved to the desired location. It will be understood that the clamping or gripping member 48 may be engaged with the log adjacent one end thereof so as to raise one end and permit the log to be dragged from one area to another.

This hoist or crane has been designed particularly for use in raising and moving relatively small logs from swampy or soft ground.

What is claimed is:

A portable hoist comprising an elongated boom, a U-shaped bolster affixed to said boom intermediate the ends thereof, wheels carried by said bolster, bracing bars fixed to said boom and said bolster and converging from said bolster toward

5
10

said boom, a rectangular frame member secured to said boom and said bolster rearwardly of said bolster, journals carried by the sides of said frame member, a shaft rotatable in said journals, a drum rotatable with said shaft, a cable wound on said drum, a sheave pivotally carried by the end of said boom, said cable extending over said sheave, a log gripping member secured to the end of said cable, a source of power, a clutch, a drive shaft including a universal joint connected to said clutch and said source of power, a connection between the clutch and said drum for rotating said drum, and hydraulic brake means for said drum.

HAYES W. BEATTY.
